UNITED STATES PATENT OFFICE

168,537

DECORATIVE LAMP

Emil C. Fasson, Inglewood, Calif.

Application June 11, 1952, Serial No. 20,127

Term of patent 14 years

(Cl. D26—8)

To all whom it may concern:

Be it known that I, Emil C. Fasson, a citizen of the United States and resident of Inglewood, in the county of Los Angeles and State of California, have invented a new, original, and ornamental Design for a Decorative Lamp, of which the following is a specification, reference being had to the accompanying drawing, forming a part thereof;

Figure 1 is a front elevational view of a decorative lamp showing my new design;

Figure 2 is a side elevational view; and

Figure 3 is a cross-sectional view taken along line 3—3 of Figure 1.

The dominant features of my design are shown in solid lines in the drawing.

I claim:

The ornamental design for a decorative lamp, substantially as shown and described.

EMIL C. FASSON.
